Patented Oct. 2, 1917.

Inventor
REGINALD C. STEEPLE,

By *Joshua C. Post*

Attorney

UNITED STATES PATENT OFFICE.

REGINALD C. STEEPLE, OF SPOKANE, WASHINGTON.

CHANDELIER.

1,241,777.

Specification of Letters Patent.

Patented Oct. 2, 1917.

Application filed April 8, 1916. Serial No. 89,740.

To all whom it may concern:

Be it known that I, REGINALD C. STEEPLE, a citizen of the United States, residing at Spokane, county of Spokane and State of Washington, have invented certain new and useful Improvements in Chandeliers, of which the following is a specification.

My invention relates to chandeliers, that is, to devices for supporting sources of artificial light from the ceiling. More specifically my invention relates to fixtures of this class for electric lamps comprising generally a suspended bowl arranged to inclose the electric lamp, or source of light, and a reflector of greater diameter than the bowl arranged over the same, the bowl being formed of translucent, light diffusing material and the reflector being preferably of the same or similar material.

The object of my invention is to provide means for readily adjusting the position of the bowl vertically with relation to the reflector, which means is also applicable for leveling or truing the bowl. A further object of my invention is to provide means for adjusting the lamp socket vertically with relation to the bowl and reflector. A further object of my invention is to provide, in a fixture of the class mentioned, means whereby both the bowl and the reflector may be readily removed and replaced either for the purpose of cleaning or for substituting one design or color of elements for another. A further object of my invention is to provide a device of the class mentioned adapted for use in conjunction with electric lamps of any standard or special design; and in which the lamps may be readily replaced. A further object of my invention is to provide in a device as mentioned means for properly ventilating the same. Other objects will appear hereinafter.

With these objects in view my invention consists generally in a lamp socket equipped with suitable supporting means, a shade holder supported by said socket and inclosing the same, a bowl suspended from said shade holder, formed of translucent material and adapted to inclose the lamp depending from the socket, a reflector arranged above said bowl and means for detachably connecting the reflector to the shade holder. My invention further consists in a device as above mentioned further characterized by equipping the supporting members of the

bowl with means for adjusting their length to vary the relative position between the bowl and the reflector and for leveling the former. My invention further consists in various details of construction and arrangements of parts, all as will be fully described hereinafter and particularly pointed out in the claims.

My invention will be more readily understood by reference to the accompanying drawings forming a part of this specification, and in which—

Figure 1 is a side elevation of a chandelier or electric light fixture embodying my invention in its preferred form.

Fig. 2 is a detail vertical section through the shade holder and adjacent parts, illustrated upon an enlarged scale, and

Fig. 3 is a horizontal section on the line $\alpha-\alpha$ of Fig. 2.

Referring now to the drawings, 1 indicates a lamp socket of any preferred form and 2 an electric lamp detachably mounted thereon. The socket 1 is mounted upon a supporting member 3 which in turn may be fixed directly to the ceiling or may be supported from the ceiling in any suitable manner. In the drawings I have illustrated the same as suspended by means of the ordinary flexible chain 4. The member 3 comprises a fixture loop provided with a threaded tubular nipple 5 to which the socket 1 is directly connected as shown clearly in Fig. 2. As shown therein the socket is threaded upon the nipple and a lock nut 6 secures the same rigidly in position. The purpose of this part of the construction will appear hereinafter.

Suspended from the supporting member 3 is a shade holder 7 which is preferably formed of spun brass or other thin metal. The shade holder 7 is substantially bell-shaped and at its top is provided with an aperture 8 to receive the nipple 5. A lock nut 9 threaded upon the nipple 5 supports the holder 7 and clamps the same firmly against a collar 10 on the member 3. In assembling the device the shade holder 7 is first placed upon the nipple 5 and the lock nut 9 screwed into position. The lock nut 6 is then threaded upon the nipple, and next, the lamp socket 1. The shade holder 7 is preferably of sufficient size to completely inclose the lamp socket; and intermediate its ends it is flared abruptly outwardly, form-

ing a ledge or shoulder 11 and then turned downwardly as shown clearly in Fig. 2.

12 indicates the reflector provided with the usual central opening 13 defined by the outwardly rolled flange 14. The flanged portion 14 is adapted to extend into the lower portion or mouth of the shade holder 7 and the reflector is supported in position by a plurality of screws 15 threaded through the member 7 to engage the flange 14 in the manner well known.

16 indicates the bowl which is formed of translucent light diffusing material and is of sufficient size to receive the light emitting portion of the lamp 2. The bowl 16 is supported by means of a plurality, preferably three, of members 17 extending downwardly from the shoulder 11 to which they are attached. The members 17 are preferably small flexible chains secured to the bowl 16 by ornamental studs 18. The upper ends of the members 17 are secured to eyes 19 of vertically disposed bolts 20 which extend loosely through suitable apertures in the shoulder 11 and which are equipped with nuts 21 resting upon the upper face of said shoulder.

It is obvious that by manipulation of the nuts 21 the height of the bowl 16 may be readily adjusted and also that by this means the bowl may be leveled. By means of the threaded connection of the socket 1 with the nipple 5 the said socket may be vertically adjusted with relation to the reflector 12 and the bowl and after adjustment, secured in position by means of the nut 6. It is also obvious that the several members may be readily removed for the purpose of cleaning or for replacing by similar members of different form or color to suit the taste. To furnish proper ventilation for the fixture the side walls of the shade support 7 is provided with suitable vent openings 22.

I claim:

- 45 1. In a device of the class described, a support, a lamp socket and shade holder mounted upon said support, a lamp carried by said socket, a reflector and bowl supported by said shade holder and means for adjusting said bowl vertically, substantially as described.
- 50 2. In a device of the class described, a support, a lamp socket and shade holder fixed to said support, a reflector mounted upon said shade holder, a bowl and a plurality of supporting members connecting said bowl to said shade holder, and means

for adjusting said supporting members individually, substantially as described.

3. In a device of the class described, a support, a lamp socket and shade holder fixed to said support, a reflector detachably mounted upon said holder, said holder being provided with a shoulder formed with a plurality of perforations, eye bolts extending through said perforations, nuts on said bolts resting upon said shoulder, a bowl and supporting members fixed at one end to said bowl and at the other end, to said eye bolts, substantially as described. 70

4. In a device of the class described, a support, a shade holder fixed to said support, a lamp socket mounted for vertical adjustment on said holder, a reflector carried by said holder, a bowl suspended from said holder, and means for adjusting said bowl vertically, substantially as described. 75

5. In a device of the class described, a support provided with a vertically disposed threaded nipple, a shade holder comprising a bell shaped member provided in its upper end with an aperture to receive said nipple, a nut threaded upon said nipple and supporting said holder, a lamp socket threaded upon said nipple, a reflector carried by said holder, a bowl suspended from said holder, and means for adjusting said bowl vertically, substantially as described. 85

6. A one-piece socket cover of substantially bell shape adapted for receiving and supporting the neck of a shade or reflector, chains for supporting a lower bowl, and means suspended inside said socket cover adapted to connect with and support said chains. 95

7. In a device of the class described, a bell-shaped socket cover having its lower end flared for the reception of the neck of a shade or reflector, means directed through the lower end of said cover for clamping said neck within said flared end, a plurality of chains to support a lower bowl, and means to support said chains from the cover, said last-named means being suspended on the inside of said cover and terminating adjacent to said neck. 100

In testimony whereof I have signed my name to this specification in the presence of two subscribing witnesses.

REGINALD C. STEEPLE.
